Primary Examiner — Sheryl Lane*Assistant Examiner* — Aula Soroush(74) *Attorney, Agent, or Firm* — Nixon & Vanderhye P.C.(57) **CLAIM**

The ornamental design for a cushion for patient interface, as shown and described.

DESCRIPTION

FIG. 1 is a front perspective view of a cushion for patient interface showing a first embodiment of our new design; FIG. 2 is another perspective view thereof showing the cushion in isolation;

FIG. 3 is a front view thereof;

FIG. 4 is a rear view thereof;

FIG. 5 is a top view thereof;

FIG. 6 is a bottom view thereof;

FIG. 7 is a left side view thereof;

FIG. 8 is a right side view thereof;

FIG. 9 is a front perspective view thereof;

FIG. 10 is a front perspective view of a cushion for patient interface showing a second embodiment of our new design;

FIG. 11 is another perspective view thereof showing the cushion in isolation;

FIG. 12 is a front view thereof;

FIG. 13 is a rear view thereof;

FIG. 14 is a top view thereof;

FIG. 15 is a bottom view thereof;

FIG. 16 is a left side view thereof;

(Continued)

(Continued)

FIG. 17 is a right side view thereof; and, FIG. 18 is a rear perspective view thereof. Where included stippling, textile shading and/or line shading are used to denote different materials.

1 Claim, 6 Drawing Sheets

Related U.S. Application Data

continuation of application No. 29/702,629, filed on Aug. 21, 2019, now Pat. No. Des. 930,150.
